AUTOMATIC BLOCK SIGNALING SYSTEM
FOR RAILROADSGeorge T. Callahan, Washington, D. C., assignor
to General Railway Signal Company, Roches-
ter, N. Y.

Application October 15, 1938, Serial No. 235,255

10 Claims. (Cl. 246—33)

This invention relates to automatic block signaling systems for single track railroads of the type commonly known as absolute-permissive-block systems, and more particularly pertains to such systems employing five indication signals.

In the usual absolute-permissive-block system, such as disclosed, for example, in the patent to S. N. Wight, No. 1,294,736, dated February 18, 1919, after a train enters a stretch of single track the tumble-down of all of the line relays for the opposing signals for that stretch of track renders the line circuits for those relays de-energized and idle. This invention makes use of certain ones of the line wires in such idle line circuits for providing that the intermediate signals shall each give an indication in addition to the usual four indications.

Thus five distinctive indications are provided for each signal, namely; a clear indication is provided when one wire of the line circuit for that signal is energized together with one of the idle line wires for an opposing signal; an approach-medium indication is provided when the line circuit for that signal is energized positive; an approach indication is provided when the line circuit for that signal is energized negative; a stop-and-proceed indication is provided when the line circuit for that signal is deenergized, and its stick relay is energized; and an absolute stop indication is provided when the line circuit and the stick relay for that signal is deenergized.

Other objects, purposes and characteristic features of the invention will be in part obvious from the accompanying drawings and in part pointed out as the description of the invention progresses.

In describing the invention in detail reference will be made to Figs. 1A and 1B, which, when placed end to end, constitute a plan showing one embodiment of the present invention, and in which like reference characters (provided with distinctive exponents or preceding numerals) designate similar parts throughout both drawings.

With reference to the accompanying drawings, a stretch of single track has been shown having signals associated therewith for governing traffic in both directions, of which signals S⁴, S⁶, S⁸ and S¹⁰ have been shown for governing east-bound traffic, toward the right; and signals S⁵, S⁷, S⁹ and S¹¹ have been shown governing west-bound traffic, toward the left.

The stretch of track is divided into blocks,

each of which is composed of two track sections insulated from each other by the usual insulated joints, and each track section having a track relay energized from the track battery by the usual track circuit, of which track relays 2TB, 5TA, 4TB, 6TA, 6TB, 8TA, 8TB, and 10TA have been shown.

The signals have been shown as being of the color position light type, having in addition to the position light signal unit, a white lamp W directly above the unit and another white lamp W¹ above and to the left of the unit. Such a combination of signal lamps provides the following distinctive indications. The illumination of two green lamps G, one above the other, in combination with the illumination of the white lamp W directly above the unit, provides a clear indication. The illumination of two green lamps G, one above the other, in combination with the illumination of the white lamp W¹ above the unit and to the left, provides an approach-medium indication. The illumination of two yellow lamps Y, one above the other and at a 45° angle to the right, in combination with the illumination of the white lamp W directly above the unit, provides an approach indication. The illumination of two red lamps R, both in a horizontal plane, in combination with the illumination of the white lamp W directly above the unit, provides a stop-and-proceed indication. The illumination of two red lamps R, both in a horizontal plane, with both of the white lamps W and W¹ extinguished, provides an absolute-stop indication. It is of course to be understood that other means for displaying the indications could as well be employed, all within the scope of the present invention.

The relays HD, PC and S are of the type commonly employed in absolute-permissive-block signaling, and the control of these relays is well known to those familiar with the art.

The relay AD is a neutral type relay which is used for selecting the control of the white lamps, and the control circuit for this relay includes one of the line wires used for controlling the HD relay associated with the control of an opposing signal.

For the purpose of simplifying the illustration and facilitating in the explanation thereof the various parts and circuits constituting the embodiment of the invention have been shown diagrammatically and certain conventional illustrations have been employed, the drawings having been made more with the purpose of facilitating the disclosure as to the principles and mode

- of operation, than with the idea of illustrating the specific construction and arrangement of parts that would be employed in practice. Thus, the various relays and the contacts have been 5 illustrated in the conventional manner and symbols are used to indicate connection to the terminals of batteries, or other sources of electric current, instead of showing all of the wiring connections to these terminals.
- 10 The symbols (+) and (--) are employed to indicate the positive and negative terminals respectively of suitable batteries, or other sources of direct current, and the circuits with which those symbols are used always have current flowing in the same direction.

15 It is believed that novel features of this invention can best be understood by considering operation of the system during the passage of trains.

20

Operation

- In view of the fact that the apparatus for each signal location is similar to that used at other locations, in order to simplify the disclosure, conditions of the apparatus at certain signal locations under various traffic conditions will be described in detail, and these conditions are to be considered as typical of conditions which exist under similar traffic conditions at any of the other signal locations.
- 30 Under normal conditions, with the track section unoccupied the relay HD for each signal is energized over a line circuit extending to the next signal in advance for governing traffic in the same direction; as, for example, relay 6HD is energized by a circuit closed from (+), through back contact 20 of relay 9S, front contact 21 of relay 8PC, front contact 22 of relay 6TB, wire 23, front contact 24 of relay 6TA, winding of relay 6HD, wire 25, front contact 26 of relay 40 6TB, front contact 27 of relay 8PC, and back contact 28 of relay 9AD, to (--) .

When relay 6HD is picked up, a circuit is closed for energizing relay 6PC from (+), through front contact 29 of relay 6HD and winding of relay 6PC, to (--) .

Under normal conditions the relays 6S and 6AD are deenergized, and a circuit is closed for energizing the white lamp W¹ in signal S⁶ from (+), through front contact 30 of relay 6PC, polar contact 31 of relay 6HD in a right-hand position, back contact 32 of relay 6AD and lamp W¹, to (--) . At the same time a circuit is closed for energizing the green lamps G in signal S⁶ from (+), through front contact 33 of relay 5PC, polar contact 34 of relay 6HD in a right-hand position, and both of the lamps G connected in multiple, to (--) .

Thus, under normal conditions with the track circuits for the stretch of single track unoccupied each signal displays an approach medium indication if approach lighting for the signal lamps is not provided.

In order that the drawings can clearly show the conditions of the relays under various traffic conditions an east-bound train K has been shown as having entered block 10, and, due to the fact that the idle line wire for the control of the relay HD for an opposing signal is used to govern the clear indication of a signal, it has been necessary to show a second east-bound train K¹ approaching signal S⁴ in block 2, in order to show all four proceed indications in a successive order as they are provided in practice. If the second train K¹ were not present the relay 5HD would be in its energized condition, resulting in the

picking up of relay 5PC, thereby opening the circuit for the relay 4AD at back contact 46. Dropping of relay 4AD would close the energizing circuit for relay 7HD, and so on, causing all of the west bound signals of that single track section to the rear of train K to give an approach-medium indication.

When a train approaches a signal, if the first three blocks in advance of that signal are unoccupied, a clear indication is provided for that train by the illumination of two green lamps G, one above the other, in combination with the illumination of the white lamp W directly above the position light unit, such as is shown for signal S⁴ when the train K¹ is approaching that signal.

Under the conditions shown at signal S⁴ relay 4HD is energized with positive energy to operate its polar contacts to a right-hand position, by a circuit closed from (+), through back contact 35 of relay 7S, front contact 36 of relay 6PC, front contact 37 of relay 4TB, front contact 38 of relay 4TA, winding of relay 4HD, front contact 39 of relay 4TB, front contact 40 of relay 6PC, and back contact 41 of relay 4AD, to (--) .

Relay 4AD is also energized, under the conditions shown, from the next signal in advance which is S⁶, over a line circuit including one of the line wires used for the control of relay 4HD and one of the line wires used for the control of relay 7HD. Relay 4AD is energized by a circuit closed from (+), through back contact 35 of relay 7S, front contact 36 of relay 6PC, polar contact 42 of relay 6HD in a right-hand position, front contact 43 of relay 6HD, back contact 44 of relay 7HD, front contact 45 of relay 4TA, back contact 46 of relay 5PC, back contact 47 of relay 5S, winding of relay 4AD, front contact 48 of relay 4HD, front contact 39 of relay 4TB, front contact 40 of relay 6PC, and back contact 41 of relay 7AD, to (--) .

It will be noted in tracing the circuit for relay 4AD that the circuit included a polar contact 42 on relay 6HD in a right-hand position, which provides that relay 4AD can be energized only when signal S⁶ is either clear or at approach medium, and that the circuit also includes a selection of a back contact 44 on relay 7HD to open the circuit for relay 4AD whenever the line circuit for the opposing signal is being used.

Relay 4PC is energized by a circuit closed from (+), through a circuit including front contact 49 of relay 4HD and winding of relay 4PC to (--) ; and the picking up of relay 4PC closes a circuit, for energizing the green lamps G in signal S⁴, from (+), through front contact 50 of relay 4PC, polar contact 51 of relay 4HD in a right-hand position, and both of the green lamps G, connected in multiple, to (--) . At the same time a circuit is closed for energizing the white lamp W in signal S⁴, from (+), through front contact 52 of relay 4PC, polar contact 53 of relay 4HD in a right-hand position, front contact 54 of relay 4AD and white lamp W, to (--) .

Assume the train K to have advanced in an easterly direction to section 10, having passed signals S⁴, S⁶, S⁸ and S¹⁰, and to have caused the dropping of relay 10TA by having shunted its track circuit. The dropping of track relay 10TA opens the control circuit for relay 10HD at front contact 55, and the dropping of relay 10HD opens the control circuit for relay 10PC at front contact 56.

The stick relay 10S is energized in the usual manner, it being picked up when relay 10TA

drops and before relay 10PC drops away, at which time a circuit is closed from (+), through back contact 57 of relay 10TA, front contact 58 of relay 10PC and winding of relay 10S, to (-); 5 and the picking up of that relay closes a stick circuit through front contact 59 to shunt out contact 58 of relay 10PC.

The red lamps R for signal S¹⁰ are energized under the above conditions by a circuit closed 10 from (+), through back contact 60 of relay 10PC and both of the red lamps R connected in multiple, to (-); and at the same time a circuit is closed for energizing the white lamp W for that same signal, from (+), through front contact 15 61 of relay 10S and white lamp W, to (-).

Had the train K been proceeding in a westerly direction through track section 10, it is obvious that the circuit for the control of the white lamp W would have been opened at front contact 61 20 of relay 10S, thus causing the signal to display an absolute-stop indication by illuminating the red lamps R only, in a manner shown for each of the opposing signals S⁵, S⁷, S⁹ and S¹¹.

With relay 10PC in a dropped away position, a 25 circuit is closed for energizing relay 8HD, for the next signal in the rear, with negative polarity so as to cause the operation of its polar armature to its left-hand position, from (+), through back contact 62 of relay 11S, front contact 63 of relay 10S, back contact 64 of relay 10PC, front contact 65 of relay 8TB, winding of relay 8HD, front contact 66 of relay 8TA, front contact 67 of relay 8TB, back contact 68 of relay 10PC and back contact 69 of relay 11AD, to (-).

35 The picking up of relay 8HD closes a circuit for energizing relay 8PC from (+), through front contact 70 of relay 8HD and winding of relay 8PC, to (-).

The above conditions cause the display of an 40 approach indication at signal S⁸ by the energization of the yellow lamps Y, from (+), through a circuit including front contact 71 of relay 8PC, polar contact 72 of relay 8HD in a left-hand position, and both of the lamps Y connected in multiple, to (-); and at the same time the white lamp W is energized from (+), through a circuit including front contact 73 of relay 8PC, polar contact 74 of relay 8HD, in a left-hand position, and white lamp W, to (-).

50 The picking up of relay 8PC closes a circuit for energizing relay 6HD with positive polarity, to operate its polar armature to a right-hand position, in the same manner as has heretofore been described for the control of that relay. The 55 picking up of relay 6HD caused the energization of relay 6PC and circuits are closed for energizing the green lamps G and the white lamp W¹ for signal S⁶ through circuits which have already been described, the lamp W¹ having been illuminated because the circuit for the control of relay 6AD is opened at polar contact 75 of relay 8HD.

It is thus seen that insofar as the green, yellow and red lamps are concerned of each of three 60 signals in the rear of a train they are controlled 65 in accordance with usual absolute-permissive-block signaling practice, that is, the first signal to the rear is caused to indicate red because its home relay and its associated pole changer relay are deenergized, the second signal to the rear of a train is caused to indicate yellow because the stick relay at the signal next in advance thereof has been energized as a result of which the home relay associated with such second signal is energized by current of reverse polarity, and the 70 third signal in the rear of the train is energized 75

to give a green indication because the home relay and its associated pole changer relay of the signal next in advance of such third signal is energized. It will also be seen that the fourth signal to the rear of a train will give the same 5 indication insofar as the green, yellow and red lamps are concerned as the third signal in the rear. Referring now to the two white lamps W and W¹, it will be seen that the lamp W can be energized only if either the associated stick relay 10 S is energized (see signal S¹⁰), if the associated pole changer relay PC and the associated relay AD are energized and the polar contacts of the home relay are in their normal position (see signal S⁴), or the pole-changer relay is energized 15 with the polar contacts of the home relay in their reverse polarity position (see signal S⁸). Also, it will be seen that the white lamp W¹ can be energized only if the associated home relay is energized by current of reverse polarity, the 20 associated pole changer relay is energized and the associated relay AD is deenergized, (see signal S⁶). From this consideration it is apparent that if the train K¹ (see Fig. 1A) were not present in block 2 the relay 5HD would be energized 25 instead of deenergized, resulting in the energization of the relay 5PC. Also, if this relay 5PC is energized the circuit for energizing the relay 4AD would be broken at the back contact 46 of relay 5PC so that the lamp W¹ would be energized instead of the lamp W. Stating it differently, the 30 fourth or clear indication to the rear of a train is not given at the fourth signal to the rear of such train unless there is a train approaching 35 such fourth signal. In other words, the tumble-down circuits for one direction of travel produces the effect of an approach control for the other direction of travel. Also upon entrance of a train into a single track section, and the deenergization of all the home relays for the 40 reverse direction of travel by the deenergization of the tumble-down circuits, the signals for this reverse direction of travel will have both of their white lights deenergized thereby giving absolute-stop indications. This is true because both the 45 pole changer relay and the directional stick relay for each of these signals are both deenergized, thus removing all energy from the white light circuits.

Having described the control of certain double 50 intermediate signals for a stretch of single track as one specific embodiment of the present invention, it is desired that it be understood that this form is selected to facilitate the description of the invention rather than to limit the number 55 of forms which it may assume, and it is to be further understood that various modifications, adaptations and alterations may be applied to the specific forms shown to meet the requirements of practice, without departing in any manner from the spirit or scope of the present invention except as limited by the appended claims.

What I claim is:

1. In a block signaling system for railroads; a stretch of single track having signals for governing traffic in both directions; a polar-neutral relay for each signal; circuit means including line wires extending to the next signal in advance for governing traffic in the same direction for energizing said polar-neutral relay in accordance with the distinctive polarity of energization of such line wires from a source of current at such signal in advance; a neutral relay for each signal; circuit means for energizing said neutral relay, only if the polar-neutral relay 65 70 75 75

at the next signal in advance for governing traffic in the same direction is energized by current of a particular polarity, said circuit means including a line wire for controlling the polar-
5 neutral relay for an opposing signal, and being closed only if the polar-neutral relay for that opposing signal is in a dropped away position; and circuit means including contacts of said polar-neutral and said neutral relays for causing 10 each signal to display a distinctive indication when said polar-neutral relay and said neutral relay for that signal are both picked up.

2. In a block signaling system for railroads; a stretch of single track having signals for governing traffic in both directions, a polar-neutral relay for each signal; circuit means for energizing said polar-neutral relay including line wires extending to the next signal in advance governing traffic in the same direction and energized by 15 current of one or another polarity; circuit means including contacts of said polar-neutral relay for causing each signal to indicate approach-medium when the polar-neutral relay for that signal is energized by current of one polarity; a circuit 20 means including contacts of said polar-neutral relay for causing each signal to indicate approach when the polar-neutral relay for that signal is energized by current of the opposite polarity; circuit means including contacts of said 25 polar-neutral relay for causing each signal to indicate stop when the circuit for the control of the polar-neutral relay for that signal is open; a neutral relay for each signal; circuit means including contacts of the polar-neutral relay at 30 the signal in advance for energizing each of said neutral relays when the signal in advance for governing traffic in the same direction indicates clear or approach--medium, providing there is a train in said stretch of single track approaching 35 the signal under consideration, through a circuit including a line wire for the control of a polar-neutral relay for an opposing signal; and circuit means including contacts of said polar-neutral relay and said neutral relay for causing each 40 signal to indicate clear when said polar-neutral relay and said neutral relay for that signal are both picked up.

3. In an absolute-permissive-block signaling system for railroads, a stretch of single track 50 having signals for governing traffic in both directions; a polar-neutral relay for each signal; circuit means including line wires for energizing said polar-neutral relay in accordance with the distinctive polarity of energization of said line wires, 55 said line wires extending to the next signal in advance for governing traffic in the same direction; circuit means including contacts of said polar-neutral relay for causing each signal to indicate approach-medium when the line wires for 60 that signal are energized by current of one polarity; circuit means including contacts of said polar-neutral relay for causing each signal to indicate approach when the line wires for that signal are energized by current of the opposite polarity; 65 circuit means including contacts controlled by said polar-neutral relay for causing each signal to indicate stop-and-proceed for following trains and to indicate absolute-stop for opposing trains on that stretch of track when the circuit for the 70 control of the polar-neutral relay for that signal is opened; a neutral relay for each signal; circuit means including contacts of the polar-neutral relay of the signal in advance for energizing each of said neutral relays when the next signal 75 in advance for governing traffic in the same di-

rection indicates clear or approach-medium, providing there is a train in said stretch of a single track approaching the signal under consideration, through a circuit including a line wire for the control of a polar-neutral relay for an opposing signal; and circuit means including contacts of said polar-neutral relay and said neutral relay for causing each signal to indicate clear when said polar-neutral relay and said neutral relay for that signal are both picked up.

4. In an absolute-permissive block signaling system for railroads, a stretch of single track having signals for governing traffic in both directions; a pole changing relay for each signal controlled in accordance with the occupied condition of the track in advance of that signal; a stick relay for each signal energized only if a train has accepted that signal and has not yet passed the next signal in advance; circuit means including contacts of said pole changer relay and said stick relay for causing lamps indicating stop-and-proceed to be illuminated when said stick relay is picked up, if said pole changer relay for that signal is in a dropped-away position; and circuit means including contacts of said pole changer relay for causing lamps indicating absolute-stop to be illuminated when said stick relay and said pole changing relay for that signal are both in a dropped-away position.

5. In an absolute-permissive-block signaling system; the combination with a single track section; a plurality of signals for governing traffic in each direction over said section; a stick relay for each signal; a pick-up circuit for each stick relay closed only when a train passes the associated signal in the direction it governs traffic; a stick circuit for each stick relay closed only so long as the block in advance of the associated signal is occupied; a polarized home relay for each signal energized by current of one polarity if two blocks in advance are unoccupied, energized by current of reverse polarity if the block in advance is unoccupied and the stick relay associated with the signal in advance is energized, and deenergized if the block in advance is occupied; 40 a special relay also governed in accordance with traffic conditions in advance; circuit means including contacts on said home relay, said stick relay and said special relay for governing the associated signal; and means including the home relay for a signal governing traffic in an opposite direction which will be deenergized by a train entering the said section in the normal direction for 45 causing a signal for the normal direction of travel to give an indication in accordance with the condition of indication of said home relay said stick relay and said special relay for that signal.

6. In an absolute-permissive-block signaling system; the combination with a single track section; a plurality of signals for governing traffic in each direction over said section; a stick relay for each signal; a pick-up circuit for each stick relay closed only when a train passes the associated signal in the direction it governs traffic; a stick circuit for each stick relay closed only so long as the block in advance of the associated signal is occupied; a polarized home relay for each signal energized by current of one polarity if two blocks in advance are unoccupied, energized by current of reverse polarity if the second block in advance is occupied and the stick relay associated with the signal in advance is energized, and deenergized if the block in advance is occupied; other means for controlling each signal; and approach control means for each signal

to cause proper indication of such signal by said home relay and said other means when there is a train approaching such signal including a home relay for a signal governing traffic in the opposite direction.

- 5 7. In an absolute-permissive-block signaling system; the combination with a stretch of single track; a plurality of successive signals for governing traffic in each direction over said stretch; 10 a polarized home relay for each signal; a pair of wires for each signal extending to the next signal in advance; means including said home relay for each signal to cause such signal to give three aspects depending on whether the associated 15 home relay is energized by current of normal polarity over the associated pair of line wires, is energized by current of reverse polarity over the associated pair of line wires or is deenergized; and means for causing each signal to give a 20 fourth aspect including one of the wires of the pair of line wires for said signal extending to the next signal in advance and one of the line wires of a pair of line wires associated with a signal for governing traffic in the opposite direction.
- 25 8. In an absolute-permissive-block signaling system; the combination with a stretch of single track; a plurality of successive signals for governing traffic in each direction over said stretch; a polarized home relay for each signal; a pair of 30 wires for each signal extending to the next signal in advance; means including said home relay for each signal to cause such signal to give three aspects depending on whether the associated home relay is energized by current of normal 35 polarity over the associated pair of line wires, is energized by current of reverse polarity over the associated pair of line wires or is deenergized; and means for causing each signal to give a fourth aspect including a special relay; and an 40 energizing circuit for said special relay including contacts of the home relay next in advance closed only if such home relay in advance is energized by current of normal polarity and including contacts closed only if the home relay 45 for the adjacent signal governing traffic in the opposite direction is deenergized.
9. In an absolute-permissive-block signaling system; the combination with a stretch of single track; a plurality of successive signals for governing traffic in each direction over said stretch; a polarized home relay for each signal; a pair of wires for each signal extending to the next signal in advance and including front contacts
- of track relays of the block extending from such signal to the signal next in advance; means including said home relay for each signal to cause such signal to give three aspects depending on whether the associated home relay is energized 5 by current of normal polarity over the associated pair of line wires, is energized by current of reverse polarity over the associated pair of line wires or is deenergized; and means for causing each signal to give a fourth aspect including a 10 special relay; and an energizing circuit for said special relay including contacts of the home relay next in advance closed only if such home relay in advance is energized by current of normal polarity, including back contacts of a directional stick relay for the adjacent signal governing traffic in the opposite direction which directional stick relay is energized only by the passage of a train in such opposite direction, and including contacts closed only if the home relay 15 for the adjacent signal governing traffic in the opposite direction is deenergized.
10. In a block signaling system of the absolute-permissive block type for railroads, a stretch of single track having signals for governing traffic 20 in both directions by permissively governing traffic to the rear of a first train and by absolutely blocking an opposing train, a polar-neutral relay for each signal, circuit means including only two line wires for each signal extending to the next signal in advance for governing traffic in the same direction for energizing said polar-neutral relay with current of one polarity or another in accordance with whether the corresponding polar-neutral relay at such signal in 25 advance is energized or de-energized through the medium of the associated two line wires from a source of current at such signal in advance, a neutral relay for each signal, circuit means including one of said two line wires for such signal 30 and one of said two line wires for the opposing signal next in advance for energizing said neutral relay or leaving it de-energized in accordance with the distinctive polarity of energization of the polar-neutral relay for the next signal in 35 advance governing traffic in the same direction, and circuit means including contacts controlled by said polar-neutral relay and contacts of said neutral relay for causing each signal to display a distinctive indication when said polar-neutral 40 relay and said neutral relay for that signal are both energized.
